UNITED STATES PATENT OFFICE

MUIR ANDERSON, OF CHICAGO HEIGHTS, ILLINOIS

LOOM

Application filed May 13, 1929. Serial No. 362,623.

My invention relates to improvements in looms and more particularly to a new and improved operation of weaving a marker in the fabric.

5 My invention is particularly applicable to the type of loom known as the "jacquard" machine wherein the weaving is controlled by a perforated pattern.

In the weaving of fabric, say for bed-spreads, or the like, it is customary to run off the fabric from the loom and cut it thereafter into desired lengths, obviously leaving end pieces of odd sizes which cannot be used, say as bedspreads, and which must be discarded as waste.

10 It is obvious that this waste is considerable and causes a loss which increases the cost of manufacture. No means have heretofore been provided in so far as I am aware, which 20 measured the length of the fabric being woven on the loom, by a marker in the fabric, so that the machine might be stopped at the proper time.

15 My invention contemplates eliminating this waste by providing improved means associated with the pattern cylinder which functions to interrupt the advancing movement of this cylinder, in its timed relation with the movement of the shuttle, whereby 25 the shuttle will be caused to place a number of picks together in the fabric, by several successive operations, which picks are readily noticeable and will serve as a marker to permit the fabric to be quickly and conveniently cut into proper lengths. Accordingly, 30 this waste is entirely eliminated.

A further object of the invention is to provide the aforesaid means as an appliance 40 capable of attachment to various types and sizes of looms without necessitating changes in construction or operation of the looms.

45 Specifically, I prefer to embody the invention in the form of a pawl and ratchet mechanism having a cam thereon, which may be so timed in its engagement with a tripping arm that the cylinder pawl may be held out of driving relation with the cylinder, to permit the shuttle to operate several 50 successive times without advancing the pattern.

Other objects and advantages of the invention will be apparent from the following description when taken in connection with the accompanying drawings in which,

55 Figure 1 is a view of the portion of the head of a jacquard machine illustrating my invention incorporated therein, and showing the position of the parts when the marker is being placed in the fabric by the shuttle;

Fig. 2 is a top elevational view of the pawl and ratchet mechanism which I employ;

Fig. 3 is an elevational view of this device illustrating the parts in a different position from that shown in Figure 1;

Fig. 4 is a vertical sectional view taken on line 4—4 of Fig. 3;

Fig. 5 is a view of the side of the ratchet carrying the cam;

Fig. 6 is an end view of one of the pattern cards illustrating one of a series of perforations for controlling my mechanism; 70 and

Fig. 7 illustrates the marker formed in the fabric.

Inasmuch as the construction and operation of jacquard machines are well known to those skilled in the art, I have illustrated only those parts which are related to and controlled by the mechanism embodying my invention. While I shall refer to certain 75 well known parts, such as the shuttle, a bat-ten frame and griffe operating mechanism which are not shown in the drawings, their construction and operation are understood by those skilled in the art, and accordingly 80 merely referring to them is believed sufficient 85 for a clear understanding of an adaptation of the present invention.

The weaving of picks in fabric is usually 90 controlled by a perforated pattern comprising perforated cards 5 laced together at the perforations 6.

Pattern 5 is suitably carried by a cylinder 7 which, as is well known, is adapted to reciprocate in a horizontal plane by mechanism, shown partly at 8, so that on its forward or outward stroke the corner projec-tions 9 are successively engaged by a pawl 10 whereby the cylinder is rotated a quarter 95 of a turn in counterclockwise direction. 100

Each such quarter turn of cylinder 7 presents a new card 5 of the pattern to the jacquard needles 11, which cooperate with the well-known hooks 12. Pattern cards 5 are provided with perforations 13 according to the pattern to be woven in the fabric by the bobbin. As is well understood by those skilled in the art, needles 11 are urged forwardly by the usual spring box 13' to engage in perforations 13. The number and arrangement of perforations 13 determine the number of needles 11 which move forwardly upon each quarter turn of pattern cylinder 7. The movement of needles 11 pulls hooks 12 to a position where they will be picked up by the usual griffe plates 14 upon each operation of the loom. I have not shown the frame for carrying griffe plates 14, but this may be accomplished in any well-known way, the purpose being to raise the griffe plates 14 so as to lift hooks 12. The lower end of hooks 12 are connected by neck cords 15, which neck cords project downwardly to control the movement of the warp as the shuttle moves back and forth across the bed. For each crosswise movement of the shuttle, pattern cylinder 7 is rotated a quarter of a turn to present a new pattern card 5 to needles 11.

The number of pattern cards furnished in one pattern depends upon the design to be woven. Also, the number of hooks 12 employed depends upon the number of needles 11 used. Most machines furnish extra hooks at the sides which may be used for various purposes. I prefer, however, to connect one of these extra hooks designated specifically as 16 with a cord 17 to a pawl arm 18, pivotally connected at 19 to a bracket member 20. As indicated in Figures 1 to 3, inclusive, pawl arm 18 is furnished with a pawl 21 pivotally carried at 22, the rear end of this pawl being urged upwardly by a spring 23. Pivot 19 is preferably at one end of pawl arm 18. A ratchet 24 is mounted on pivot 19 so that pawl 21 may engage the same and advance the ratchet one step upon each movement of arm 18. The usual back stop pawl 25 may be provided to prevent reverse rotation of ratchet 24.

A cam plate 26 may be furnished on the inside face of ratchet 24. This cam plate 26 is provided with a cam 27 projecting above the teeth on ratchet 24 whereby upon each complete rotation of this ratchet, cam 27 will engage a tripping arm 30 pivotally mounted at 31 to bracket plate 20. This engagement of tripping arm 30 depresses the rear end thereof so that, by means of a cord connection 32, the cylinder pawl 10 may be lifted out of driving relation with pattern cylinder 7, as illustrated by the position of the parts in Fig. 1. Cylinder pawl 10 will remain out of driving relation with pattern cylinder 7 until ratchet 24 is advanced to withdraw cam 27 from under tripping arm

30. According to the present disclosure, the number of crosswise movements of the shuttle during the period the cylinder pawl 10 is disengaged from pattern cylinder 7, depends upon the number of teeth of ratchet 24, which 70 the length of pawl 27 represents.

The operation of the device embodying my invention will now be described. A plurality of perforations 38 are punched in certain of the cards 5 so that these perforations 75 may be properly spaced along the length of the pattern, which eventually determines the distance between the markers which are placed in the fabric. For every perforation 38 I provide a tooth or ratchet 24. Engagement of needle 11 which cooperates with perforation 38 will move hook 16 to a position to be operated by one of the griffe plates 14. Accordingly, pawl arm 18 is lifted to advance ratchet 24 one tooth. At the proper 85 time, cam 27 moves forwardly to engage tripping arm 30. Such engagement lifts cylinder pawl 10 upwardly out of driving relation with pattern cylinder 7; consequently, the needles 11 will remain in their same position 90 upon the next operation of the griffe plates 14. The shuttle then moves to lay the next pick in the lay in the very same position as the former pick. The number of times the shuttle moves crosswise for laying these picks 95 together in one position in the lay, in order to provide a definite marker in the fabric, depends upon the length of cam 27. If two picks are desired, the cam 27 may be made of a length equal to two teeth as illustrated in 100 Figure 1. If the fabric is light, such as silk, it may be desirable to place a greater number of picks together to form the marker in order that this marker may be more readily noticeable.

It is obvious that the construction of the pawl and ratchet mechanism may be varied from that shown in the drawings or its location may be somewhat altered. The invention, however, resides in associating a 110 lock mechanism of this type for holding the cylinder pawl out of driving relation with the cylinder for a number of crosswise movements of the shuttle, so that more than one pick may be placed to constitute a marker in 115 the fabric.

In Fig. 7 I have illustrated the fabric with a marker 40 formed therein by the mechanism above disclosed. It will be observed that any 120 number of picks may constitute this marker 40.

Various modifications and changes may be made without departing from the spirit or scope of the invention as disclosed and claimed.

I claim:

In a loom of the class described wherein a drive advances a cylinder for a fabric pattern in timed relation with the movement of a shuttle, the combination with said cylinder 130

and fabric pattern, of an advancing pawl for advancing said cylinder in timed relation with the movement of said shuttle, a ratchet, a cam on said ratchet, a tripper arm associated with said ratchet and connected to said cylinder advancing pawl, and means for rotating said ratchet to cause said cam to lift said tripper arm whereby to disengage said cylinder advancing pawl from said cylinder.

10 In witness whereof, I have hereunto subscribed my name.

MUIR ANDERSON.
